UNITED STATES PATENT OFFICE.

THOMAS S. FOX, OF BROOKLYN, NEW YORK.

PRINTING DEVICE.

1,174,062.

Specification of Letters Patent.

Patented Mar. 7, 1916.

Application filed December 28, 1911. Serial No. 668,310.

To all whom it may concern:

Be it known that I, THOMAS S. FOX, a citizen of the United States, residing at the boroough of Brooklyn, in the county of 5 Kings and State of New York, have invented certain new and useful Improvements in Printing Devices, of which the following is a specification, reference being had therein to the accompanying drawing.

10 My invention relates to improvements in rollers such as are used by artists in rubbing down printing films, and has particular reference to the structure of such tools. Tools of this character are usually of two sizes, 15 the larger size having a roller of about one and one-half inches in diameter and the smaller size having a roller of about three-fourths of an inch in diameter. These rollers are substantially flat faced, are generally made of solid rubber except for a small 20 core, and are mounted so as to revolve at the end of a handle. In using the tool the operator runs it over the back of the inked film by hand and the lines or other characters 25 of the inked film are transferred to a plate or other surface by the hand pressure applied to the tool. The larger roller is used where considerable space is to be printed upon and the smaller roller is used 30 for smaller areas. For the other parts and detail work a stump or a stylus is generally used.

When a good taut film is used for laying down thick lines, such as what is known in 35 the trade as number 9, or "nearly a half tint", it has been frequently observed that a speckled or mottled effect is produced in the printing when the rubbing down is done by the rollers heretofore used, thus making it 40 necessary to go over the work with a stylus or other tool. That is to say, spaces or "blotches" appear in the printing, and if a line film is used, the lines will be found broken by these blank spots. I have found 45 that by using a roller of much smaller diameter a thinner line of pressure more evenly distributed can be applied and these defects will be overcome, particularly if the roller is provided with a convex face. All 50 details of the characters of the film will then print quite clearly. I have also found it preferable to use a roller having a comparatively thin surface or covering of yielding or resilient material.

Referring to the accompanying drawings 55 Figure 1 illustrates in perspective view one form of my improved roller tool. Fig. 2 is an enlarged longitudinal section of one of my improved rollers, Fig. 3 is an enlarged side elevation of the bearing pin which may 60 be used for mounting the roller within the handle or bearing of the roller tool, and Fig. 4 is an enlarged longitudinal section of another of my improved rollers.

The handle 5 terminates in a suitable 65 yoke bearing 6 within which upon a suitable axis, the roller of the tool is mounted as shown. The roller shown in Fig. 1 which is illustrated to better advantage in longitudinal section in Fig. 2, comprises a metallic 70 body portion preferably of brass indicated by the reference character 9 provided with a convex surface as shown. While this surface is shown curved in cross section it will be readily understood that a curve need not 75 be strictly followed.

10 is a yielding or resilient covering such as a piece of rubber tube which is cut of equal length to the brass body 9 and may be slipped over the same. The roller is bored 80 at 11 to provide passage for the pin 12, and this pin it will be observed has an enlarged shank at 13 and is provided with a finger lever 14.

In assembling the tool, the roller is placed 85 between the prongs of the yoke bearing 6 which are bored to admit the pin 12. This pin is then inserted through the bored holes in the ends of the prongs and through the center of the roller, and is given a twist by 90 the finger piece 14, the enlarged shank 13 binding within one of the holes or bearings, securely holding the roller in rotatable position.

15 represents a lead plug which may be 95 inserted into the yoke of the tool in any suitable manner to add weight or pressure to the roller. This weight is shown of smaller proportion for the purpose of clearness.

It will be readily understood of course 100 that instead of using a separate weight such as 15, the bearing of the tool may be made differently and of heavier material, or it may be made larger to give the same result. By using a weighted tool the pressure on the 105 roller will be more uniform throughout each stroke than when the roller is pressed upon the film by the operator.

Of course it will be understood that the roller may be mounted in any suitable manner, and various forms of mountings and handles may be used, and various means 5 may be employed for operating the tool.

The roller shown in Fig. 4 is not provided with a convex face and is much wider than the rollers shown in Figs. 1 and 2. It also shows a solid core provided with centers for 10 suitable bearings. Such rollers give excellent results.

Some films now upon the market are soft and flabby and have a tendency to loosen and sag in warm weather and with films in 15 this condition it is possible to get along with the usual larger rubber rollers but in the cold weather when these films draw up and harden the objectionable effect referred to will be encountered. Even when these soft 20 and flabby films have become hardened and drawn in the cold weather very good results can be obtained by using tools provided with rollers such as I have described. The small diameter of the roller enables pressure to be 25 applied along a sharp line of direct contact. The yielding surface is not deep enough to spread sufficiently to destroy this effect and the difference of pressure between the ends and the center of the roller may be compensated for by the enlarged center forming 30 the convex surface of the roller.

Of course relative proportions of parts might be varied to advantage under different conditions but for general purposes a 35 roller not exceeding a maximum of diameter of about five-sixteenths of an inch will be found to give very good results. Various other modifications may also be made without departing from the spirit of the invention 40 as set forth in the claims.

Copies of this patent may be obtained for five cents each, by addressing the "Commissioner of Patents, Washington, D. C."

I claim:

1. A tool for transferring characters from a printing film having a handle and a roller holder, and a roller within said holder of small diameter adapted to impart a sharp line of contact during the application of said tool whereby the details of said characters may be sharply transferred without smudging and without transferring adjacent characters from said film. 45

2. A tool for transferring characters from a printing film having a handle and a roller holder, and a roller within said holder of small diameter adapted to impart a sharp line of contact during the application of 55 said tool whereby the details of said characters may be sharply transferred without smudging and without transferring adjacent characters from said film, and in combination therewith a weight attached to said tool. 60

3. A tool for transferring characters from a printing film having a handle and a roller holder, and a roller within said holder of small diameter adapted to impart a sharp line of contact during the application of 65 said tool whereby the details of said characters may be sharply transferred without smudging and without transferring adjacent characters from said film, and a removable spindle adapted to support said roller within said holder having frictional engaging means. 70

In testimony whereof I affix my signature in presence of two witnesses.

THOMAS S. FOX.
